UNITED STATES PATENT OFFICE.

GEORGE W. COLE, OF ASBURY PARK, NEW JERSEY, ASSIGNOR TO G. W. COLE COMPANY, A CORPORATION OF NEW JERSEY.

TOE-CLIP FOR BICYCLES.

SPECIFICATION forming part of Letters Patent No. 707,209, dated August 19, 1902.

Application filed November 25, 1901. Serial No. 83,498. (No model.)

To all whom it may concern:

Be it known that I, GEORGE W. COLE, a citizen of the United States of America, and a resident of Asbury Park, State of New Jersey, have invented certain new and useful improvements in Toe-Clips for Bicycles, of which the following is a specification.

My invention relates to certain new and useful improvements in toe-clips for bicycles; and the object thereof is to form a toe-clip which will hold the foot in position on the pedal more firmly and without danger of hurting the foot of the rider and at the same time making a toe-clip which is cheaper to construct and more durable than has heretofore been possible.

With these and other objects in view the invention consists in a toe-clip which is formed of a wire bent into a general stirrup shape and a loop of leather connecting the top and bottom portions of said stirrup. By this construction a yielding toe-clip which will not injure the foot of the rider and which is more durable and cheap to manufacture is produced.

The invention also consists in certain details of construction and combination of parts, which will be first specifically described and then pointed out in the claims.

Referring to the drawings, wherein the same part is designated by the same reference-numeral wherever it occurs, Figure 1 is a perspective view of my invention. Fig. 2 is a section thereof, showing how the parts of the clip are secured together.

1 indicates a wire frame which is bent into a stirrup-like form, and the ends of this frame are bent down, as shown at 2, and form the lower part of the clip which is attached to the pedal. Preferably the lower ends of the part 2 are bent at right angles to catch under the lower side of the pedal when the clip is attached thereto.

3 indicates a bolt, and 4 a nut thereon, by means of which the clip is attached to the pedal in the ordinary manner.

5 indicates a lateral projecting offset portion which is bent out from the stirrup 1 and is of a width substantially equal to that of the strip 6.

6 indicates a strip of leather or other suit-

able material which is fastened in the projection 5 by means of a rivet 7 or in any other suitable manner, and the other end of this strip is attached to the attaching-plate 8 in 55 any suitable manner. Preferably, however, by cutting in the plate 8 the tongues 9 and bending these down through the leather, as more clearly indicated in Fig. 2, the plate 8 has an enlarged end 10, and in this end is a 60 slot 11, through which the ends 2 of the stirrup project and by means of which they are prevented from spreading. The end 10 of the plate 8 is then bent around the stirrup-wire, as is clearly shown in Fig. 2. 65

A toe-clip manufactured in the way above described is exceedingly cheap and durable. The strip of leather or other suitable material will yield when the foot is placed in the clip and conform itself to the shape of the 70 shoe of the rider. Many other advantages of this clip will be apparent to any one skilled in the art.

While I have shown and described what I believe to be the preferred form of my invention, I desire it to be understood that many changes might be made therein and parts substituted without departing from the spirit thereof. 75

What I claim as new, and desire to secure 80 by Letters Patent, is—

1. In a toe-clip for bicycles, the combination with a loop formed of wire or other suitable material, a plate uniting the ends of said loop to hold the same in position, tongues 85 bent out from said plate; a strip of leather or other suitable material, one end of which is secured to said plate by said tongues and the other end secured to said loop.

2. In a toe-clip for bicycles, the combination of a loop formed of wire or other suitable material, and provided with a laterally-projecting offset at or about the middle of said loop; a plate uniting the ends of said loop to hold the same in position; tongues bent out 95 from said plate; a strip of leather or other suitable material, one end of which is secured to said plate by said tongues, and the other end secured to said loop.

3. In a toe-clip for bicycles, the combination with a loop formed of wire or other suitable material, and provided with a laterally- 100

projecting offset at or about the middle of said loop, the ends of said wire being bent out of said loop to form part of the fastening means to secure said clip to a pedal; a plate 5 uniting the ends of said loop to hold the same in position, said plate being provided with tongues bent out from said plate; a strip of leather one end of which is secured to the laterally-projecting offset in said loop and the 10 other end secured to said plate by said tongues.

4. In a toe-clip for bicycles, the combination with a loop formed of wire or other suitable material, a clamp consisting of a bolt 15 and nut or other suitable construction for

fastening the clip to a pedal, a plate uniting the ends of said loop to hold the same in position, tongues bent out from said plate; a strip of leather or other suitable material, one end of which is secured to the plate by 20 said tongues and the other end secured to said loop.

Signed by me at New York, county and State of New York, this 19th day of November, 1901.

GEORGE W. COLE.
